UNITED STATES PATENT OFFICE.

THOMAS FEARON, OF YONKERS, NEW YORK.

STEAM-HEATER.

SPECIFICATION forming part of Letters Patent No. 484,787, dated October 25, 1892.

Application filed May 1, 1891. Serial No. 391,215. (No model.)

To all whom it may concern:

Be it known that I, THOMAS FEARON, of Yonkers, in the county of Westchester, in the State of New York, have invented new and useful Improvements in Steam-Heaters, of which the following, taken in connection with the accompanying drawings, is a full, clear, and exact description.

My invention relates to an improved steam-heater, and has for its object the production of a durable, simple, and highly-efficient construction possessing a great amount of heating-surface for producing a maximum degree of steam with a minimum amount of fuel, and capable of being readily repaired without the exercise of great skill or ingenuity and without preventing the operation of the entire boiler while a portion is being repaired.

To this end the invention consists, essentially, in a pair of steam-drums, a rectangular water-containing base, a series of upright heads or manifolds arranged alternately in two rows at the center of the heater and having their upper extremity connected to one of the steam-drums and their lower end to the water-containing base, heating-sections projecting from each of the outer faces of said heads and composed of a series of U-shaped tubes or pipes arranged one within the other with their opposite ends connected to the heads or manifolds.

The invention furthermore consists in a superheater depending from the end of the drums and mounted between the top and bottom legs of the inner U-shaped heating-tubes, in deflecting-plates also mounted between the opposite legs of said pipes for passing the heat around the superheater, and in the detail construction and arrangement of the parts, all as hereinafter more particularly described, and pointed out in the claims.

In describing this invention reference is had to the accompanying drawings, forming a part of this specification, in which like letters indicate corresponding parts in all the views.

Figures 1 and 2 represent, respectively, elevation and top plan views of my improved heater. Fig. 3 is an elevation taken at right angles to Fig. 1. Figs. 4 and 5 are horizontal sectional views taken on the respective sec-

tional lines $x x$ and $y y$, Fig. 1. Fig. 6 is an enlarged horizontal sectional view of a portion of the heads or manifolds and the heating-pipes projecting therefrom, illustrating particularly the construction and arrangement of these parts and the plug for permitting expansion of the tubes; and Fig. 7 is a horizontal sectional view of a modified form of heater.

It is well known that the aim of manufacturers of boilers designed for use in steam-launches, &c., is to make the boiler as low down as possible and at the same time provide a great amount of heating-surface, and so construct the boiler that it may be readily repaired at a minimum expense and by an ordinary pipe-fitter, and be perfectly free to expand and contract in operation.

My invention is designed to meet the above-mentioned requirements and to furnish a maximum amount of steam with a minimum amount of occupied space for the heater and required fuel.

A represents the water-containing base consisting, preferably, of a series of pipes $a a a a$, joined by elbows a' . This base may, however, be composed of a single casting, if desired.

B represents the steam-drum, of which there are preferably two, arranged lengthwise from front to back of the heater and slightly separated from each other, with their opposite ends connected to the base A by pipes B' for passing to the water-containing shell any water which may accumulate in the drum B.

C represents the upright or vertical hot-water head or manifold, arranged at the center of the heater for supporting the projecting heating-pipes D. These heads are preferably arranged in two rows and alternate with each other, as best seen at Fig. 6. The upper end of each head C is connected by a U-shaped tube or pipe c to the top portion of the farthest drum, as best seen at Figs. 1 and 2, and the bottom portion is connected by an L-shaped tube C' to the adjacent pipe a, whereby the steam passes to the steam-drum and the sediment to the cold-water-containing base A. It will be noted upon reference to the drawings that the connecting-pipes c have one or more bends and extend by and

laterally overlap each other. The heating-sections D preferably project from the outer face of the manifolds or heads C to the outer face of the grate, (not shown,) and are arranged in the form of a nest, consisting of a series of U-shaped tubes d d d d, having their opposite ends secured to or communicating with the heads C and their central portion projecting outwardly to the extreme wall of the heater. As best seen in Fig. 6, the heads are cylindrical and are provided with a nipple or plug c' for closing an opening c², arranged in the wall opposite to the entrance-opening for permitting the entrance of an expanding-tool adapted to expand the tube for holding the same firmly in position. As also seen in Fig. 6, this arrangement enables the tubes to be mounted extremely close to each other, since the projecting portion of the nipple projects into the space between the adjacent walls of the heads. It is evident, however, that instead of composing the heating-sections D of tubing they may be composed of piping, in which case the plugs c' may be dispensed with. In case one of the sections needs repair, it may be readily removed by removing the pipes c and C', and the holes for said pipes may be then plugged, and the entire heater may be operated without the injured heating-section.

E represents the superheater, having one end e depending from the drum B and the other formed with a series of coils and mounted between the opposite legs of the central heating-pipe d, as best seen at Figs. 1, 2, 3, and 5.

For the purpose of rendering the contact of the heat with the superheater more positive and certain I provide a series of bent deflecting or baffle plates E', also mounted between the opposite legs of the inner heating-tubes d and bent around the separate legs of each coil.

Upon reference to the foregoing description it is evident that the peculiar arrangement of heating-coils affords an unusual degree of heating-surface in proportion to the space occupied, and it is therefore evident that the heater or boiler may be correspondingly lowered in proportion to its capacity. Moreover, the steam is brought to an extremely-dry condition, being passed from the upper end of the drum C to the horizontal steam-drums B, from which any water is constantly drawn by the pipes B', and thence through the superheater before its passage to the engine.

The heater may be readily repaired. Its construction is simple, efficient, and durable, and permits a great amount of expansion and contraction of the parts. The water preferably enters into the lower shell A through the pipe F, and the sediment which accumulates within the lower shell A may be blown off by means of a pipe G, extending from said shell.

65 The L-shaped pipes C' form the fire-box, and for the purpose of my invention I have deemed it unnecessary to illustrate here the

fire-grate, the fire-brick, which may be placed on the outside of the pipes C', or the outer shell, all of which parts may be of the ordinary or any special construction.

At Fig. 7 I have shown a modified form of heater, in which the heads or manifolds are rectangular in cross-section and consists of separate halves C² C², adapted to be drawn together by bolts C³. These heads are illustrated as slightly separated to allow for expansion and contraction, but, if desired, may be in direct contact with each other. Projecting from the outer walls of said heads or manifolds are curved pipes arranged disposed in two rows, with the pipes alternately arranged with each other and with the outer ends of each pair curved one over the other and considerably separated in order that the entire space may be broken up and the products of combustion compelled to impart their heat to the pipes without the presence of any space of easier passage.

The operation of my invention will be readily perceived from the foregoing description and upon reference to the drawings, and it is evident that considerable change may be made in the detail construction and arrangement of the parts without departing from the spirit of my invention.

Having thus fully described my invention, what I claim as new, and desire to secure by Letters Patent, is—

1. A water-containing base, a series of upwardly-extending separate tubular heads or manifolds mounted above the substantially-central portion of the base, and projecting heating-pipes extending from opposite sides of said heads, substantially as and for the purpose set forth.

2. In combination, a steam-drum, a water-containing lower shell, a series of heads or manifolds supported above the substantially-central portion of the base and having one extremity connected to the steam-drum and the other to the lower shell, and heating-pipes extending from opposite sides of said heads, substantially as and for the purpose described.

3. In combination, a rectangular horizontal water-containing shell, a series of separate tubular vertically-extending heads or manifolds mounted above the substantially-central portion of said shell, a connection between the lower extremity of said vertical heads and the horizontal shell, and a series of projecting heating-pipes extending from the sides of said heads, substantially as and for the purpose set forth.

4. In combination, a horizontal water-containing base, a series of separate tubular vertically-extending heads or manifolds mounted above the water-containing base, a connection between the lower extremities of the vertical heads and the horizontal water-containing base, a series of U-shaped pipes projecting from the heads and arranged with both extremities opening from the same head, a steam-drum above the U-shaped pipes at one side

of the heads, and steam connections between the separate heads and the steam-drum, substantially as and for the purpose described.

5. In combination, a water-containing base, upright heads arranged above the base, L-shaped connections having one arm connected to the lower extremity of the heads and the other to the base, heating-pipes projecting from the heads and consisting of a series of 10 U-shaped pipes arranged one within the other with both extremities communicating with the heads, a steam-drum extending from front to back at the upper extremities of the heads, and connections between said steam-drum and heads, and a connecting-pipe between the steam-drum and the water-containing base, substantially as set forth.

6. In a steam-heater, the combination of a water-containing lower shell, a series of heads 20 arranged alternately with each other, heating-pipes projecting from the opposite faces of said heads, arranged oppositely with the extremity of said heating-pipes for permitting the entrance of an expanding-tool, substantially as specified.

7. In a sectional steam-boiler, the combination of two vertical drums arranged alternately, two series of pipes bent in any suitable form or outline, the pipes in one series 30 communicating at both ends with one of said vertical drums and the pipes of the other series communicating at both ends with the other of said vertical drums, both series projecting over and nearly to the outer side of the grate, and a horizontal steam-drum located over the series of pipes and fire-box and extending from the front to the rear and connected to each vertical drum by a separate 40 pipe, the latter pipes extending by and laterally overlapping each other, substantially as described.

8. In a sectional steam-boiler, the combination of two vertical drums arranged alternately, two series of U-shaped pipes, the pipes in one series communicating at both ends with one of said vertical drums and the pipes of the other series communicating at both ends with the other of said vertical 50 drums, both series projecting over and nearly to the outer side of the grate, and a horizontal steam-drum located over the series of pipes and fire-box and extending from the front to the rear of the same and connected to each vertical drum by a separate pipe having one or more bends, the several pipes 55 extending by and laterally overlapping each other, substantially as described.

9. A steam-boiler composed of a base, a series of sections each consisting of two vertical drums arranged centrally in relation to the base, two series of pipes bent into any suitable form or outline, the pipes in one series 60 communicating at both ends with one of said vertical drums and the pipes of the other series communicating at both ends with

the other of said vertical drums, both series projecting over and nearly to the outer side of the grate, and a horizontal steam-drum located over the series of pipes and fire-box 70 and extending from the front to the rear and connected to each vertical drum by a separate pipe having one or more bends, the latter pipes extending by and laterally overlapping each other, substantially as and for the 75 purpose specified.

10. A steam-boiler composed of a base, a series of sections each consisting of two vertical drums arranged centrally in relation to the base, two series of U-shaped pipes, the 80 pipes in one series communicating at both ends with one of said vertical drums and the pipes of the other series communicating at both ends with the other of said vertical drums, both series projecting inward over 85 and nearly to the opposite side of the grate, and a horizontal drum located over the series of pipes and fire-box and extending from the front to the rear of the same and connected to each vertical drum by a separate pipe 90 having one or more bends, the several pipes extending by and laterally overlapping each other, substantially as set forth.

11. In combination, a water-containing base, upright heads arranged alternately with each 95 other, and heating-pipes projecting from the opposite faces of said heads, substantially as and for the purpose specified.

12. In combination, a water-containing base, tubular upright heads or manifolds arranged 100 alternately with each other in two rows or series, and heating-pipes projecting from the opposite faces of said heads, substantially as and for the purpose described.

13. In combination, a water-containing base, 105 tubular upright heads or manifolds arranged alternately with each other in two rows or series, heating-pipes projecting from the opposite faces of said heads, and a steam-drum connected with said pipes, substantially as 110 set forth.

14. In combination, a water-containing base, tubular upright heads or manifolds arranged alternately with each other in two rows or series, heating-pipes projecting from the opposite faces of said heads, a pair of steam-drums 115 on opposite sides of the heads or manifolds, and connecting-pipes between said heads and drums, substantially as described.

15. In combination, a water-containing base, 120 tubular upright heads or manifolds arranged alternately with each other in two rows or series, heating-pipes projecting from the heads and consisting of a series of U-shaped pipes arranged one within the other, substantially 125 as and for the purpose set forth.

16. In combination, a water-containing base, tubular upright heads or manifolds arranged alternately with each other in two rows or series, heating-pipes projecting from the heads 130 and consisting of a series of U-shaped pipes arranged one within the other, and a super-

heater mounted between the arms of one of said projecting pipes, substantially as specified.

17. In combination, a rectangular frame, a steam-drum, a series of heads or manifolds arranged alternately with each other in two rows, heating-pipes having their opposite ends opening from said drums and their central portion projecting outwardly therefrom, and plugs oppositely arranged with the heating-tubes, substantially as described.

18. In combination, a rectangular water-containing shell, two rows or heads arranged alternately with each other, steam-drums on opposite sides of the upper extremities of said heads, U-shaped heating-pipes projecting from the outer faces of the heads, and a superheater connected with the steam-drum and passed through the opposite extremities of one of said heating-pipes, substantially as and for the purpose described.

19. In combination, a water-containing base, tubular upright heads or manifolds arranged alternately with each other in two rows or series, heating-pipes projecting from the heads and consisting of a series of U-shaped pipes arranged one within the other, a superheater consisting of coils mounted between the arms of one of said projecting pipes, and a series of baffle-plates bent over said superheater-coils, substantially as and for the purpose set forth.

In testimony whereof I have hereunto signed my name, in the presence of two attesting witnesses, at Yonkers, in the county of Westches- 35 ter, in the State of New York, this 15th day of April, 1891.

THOMAS FEARON.
